UNITED STATES PATENT OFFICE.

STEPHEN Q. HAYES, OF PITTSBURGH, PENNSYLVANIA, ASSIGNOR TO WESTINGHOUSE ELECTRIC & MANUFACTURING COMPANY, A CORPORATION OF PENNSYLVANIA.

CIRCUIT-INTERRUPTING SYSTEM.

1,352,451.

Specification of Letters Patent. Patented Sept. 14, 1920.

Application filed May 15, 1917. Serial No. 168,663.

To all whom it may concern:

Be it known that I, STEPHEN Q. HAYES, a citizen of the United States, and a resident of Pittsburgh, in the county of Allegheny and State of Pennsylvania, have invented a new and useful Improvement in Circuit-Interrupting Systems, of which the following is a specification.

My invention relates to systems of distribution and particularly to the circuit interrupting means therefor.

One object of my invention is to provide means for disconnecting portions of a load from a circuit, in a predetermined order, to preclude the load on the circuit from being maintained in excess of a predetermined value.

Another object of my invention is to provide a system of the above indicated character that shall be simple to construct and effective and accurate in its operation.

In practising my invention, I provide a main supply or load circuit, a plurality of branch load circuits and circuit interrupters for connecting the branch circuits to the main circuit. The trip coil of each interrupter is so controlled by auxiliary or parallel switches on the other interrupters that when the load on the main circuit exceeds the predetermined value, one interrupter at a time will be tripped until such load is removed that the load on the main circuit is reduced to the predetermined value.

The single figure of the accompanying drawing is a diagrammatic view of a system of distribution embodying my invention.

A main load circuit 1 is adapted to supply current to a plurality of loads 2, 3, 4 and 5 through branch or feeder circuits 6, 7, 8 and 9, respectively. Circuit interrupters 10, 11, 12 and 13 are connected between the respective feeder circuits 6, 7, 8 and 9 and the load circuit 1.

The circuit interrupters 10, 11, 12 and 13 severally comprise stationary contact members 14, movable bridging contact members 15, a trip coil 16 and an auxiliary double-throw switch 17 having a movable bridging contact member 18, a pair of stationary contact members 19 and a pair of stationary contact members 20. The main circuit 1 is provided with two relays 21 and 22 that are operatively connected through series transformers 23 and 24 to the circuit 1. The re-

lays 21 and 22 are adapted to be actuated to effect closure of their contact members 25 and 26 when a predetermined load traverses the circuit 1.

One terminal of the trip coil 16 of each of the circuit interrupters is connected to one conductor of the circuit 1, and the other terminal of each of the trip coils 16 is connected to one of the stationary contact members 19 of its auxiliary switch 17. The other stationary contact member 19 and the corresponding contact member 20 of the interrupter 13 are connected to a circuit 27 that is connected to one conductor of the circuit 1 and which comprises the contact members 25 and 26 of the relays 21 and 22. The corresponding contact members 19 and 20 of each of the other interrupters are connected to one of the stationary contact members 20 of its adjacent interrupter. That is, one of the stationary contact members 20 of the interrupter 13 is connected to one of the other stationary contact members 19 and 20 of the interrupter 12. Thus, when the interrupter 13 is in its open position and the interrupter 12 is in its closed position, the circuit through the trip coil 16 of the interrupter 12 is so connected in circuit with the contact members 25 and 26 of the relays 21 and 22 that if they are engaged the circuit interrupter 12 will be tripped.

When the load that traverses the circuit 1 exceeds a predetermined value it is desirable to reduce this load to a safe value and in order to obtain this, it is desirable to disconnect the loads 2, 3, 4 and 5 in a certain sequence. That is, when the load 5 is disconnected, if the load on the circuit 1 does not exceed a predetermined value, it is not desirable to disconnect the loads 2, 3, and 4. However, if the load traversing the circuit 1 still exceeds the desired value for that circuit the load 4 is disconnected, and similarly the remaining loads 2 and 3 are successively disconnected to reduce the load traversing the circuit 1 to the predetermined value.

The relays 21 and 22 are so adjusted that their contact members 25 and 26 are engaged when the load traversing the circuit 1 exceeds a predetermined value, and when the contact members 25 and 26 are engaged the trip coil 16 of the interrupter 13 is energized to trip the same. When the interrupter 13 is tripped, its auxiliary switch 17 so connects the trip coil 16 of the interrupter 12

12 in circuit with the contact members 25 and 26 of the relays 21 and 22 that should be in engagement by reason of the fact that the load on the circuit 1 has not been reduced sufficiently by the disconnection of the load 5, the interrupter 12 will be tripped. Similarly, when the interrupter 12 is tripped its auxiliary switch 17 will so connect the trip coil 16 of the interrupter 11 in circuit with the contact members of the relays 21 and 22 that if the disconnection of the loads 4 and 5 is not sufficient to reduce the load on the circuit 1 to such value that the relays 21 and 22 15 are inoperative, the circuit interrupter 11 will be tripped. In a like manner the interrupter 10 will be tripped if the disconnection of the loads 3, 4 and 5 are not sufficient to reduce the load on the circuit 1 to the 20 predetermined value that is desired not to be exceeded therein.

My invention is not limited to the specific structures illustrated nor to the method of energizing the relays and trip coils, as it 25 may be variously modified without departing from the spirit and scope of the invention as set forth in the appended claims.

I claim as my invention:

1. The combination with a main circuit, 30 a plurality of feeder circuits and interrupters for connecting the feeder circuits to the main circuit, of a relay responsive to the load in the main circuit for controlling the tripping of the interrupters, and auxiliary switches actuated by the interrupters for successively connecting the tripping devices in series with the contact members of the relay.

2. The combination with a main supply 40 circuit, a plurality of branch circuits therefor and circuit interrupters for connecting the branch circuits to the main circuit, of means responsive to the load on the main circuit for tripping the interrupters, and auxiliary switches actuated by the interrupters for successively connecting the tripping means to the main circuit.

3. The combination with a main circuit, a plurality of feeder circuits, circuit interrupters for connecting the feeder circuits to the main circuit and trip coils for the interrupters, of a relay responsive to the load on the main circuit for controlling the energization of the trip coils, and means actuated by the interrupters for successively connecting the trip coils in series with the contact members of the relay.

4. The combination with a main circuit, a plurality of feeder circuits, circuit interrupters for connecting the feeder circuits to the main circuit and trip coils for the interrupters, of a relay responsive to the load on the main circuit for controlling the energization of the trip coils, and means actuated by the interrupters for normally maintaining the circuit of the trip coils open and for connecting the same successively in series with the contact members of the relay.

5. The combination with a main circuit, a plurality of feeder circuits, circuit interrupters for connecting the feeder circuits to the main circuit and tripping devices therefor, of a relay responsive to the load on the main circuit for controlling the tripping devices, and means actuated by the interrupters for connecting the tripping devices in series with contact members of the relay in a predetermined order.

6. The combination with a main circuit, a plurality of feeder circuits, circuit interrupters for connecting the feeder circuits to the main circuit and tripping devices therefor, of a relay responsive to the load on the main circuit for controlling the tripping devices, and means actuated by the interrupters for successively connecting the tripping devices in series with the contact members of the relay to cause the interrupters to be tripped in a predetermined order.

In testimony whereof, I have hereunto 90 subscribed my name this 28th day of April, 1917.

STEPHEN Q. HAYES.
